CLAIM

We claim the ornamental design for a power entry connector, as shown and described.

DESCRIPTION

FIG. 1 is an exploded perspective view of a power entry connector, showing our new design;

FIG. 2 is a perspective view thereof, in which the power entry connector is in an assembled configuration;

FIG. 3 is a front elevation view, in which the power entry connector is in a disassembled configuration;

FIG. 4 is a rear elevation view, in which the power entry connector is in a disassembled configuration;

FIG. 5 is an exploded left-side elevation view thereof;

FIG. 6 is an exploded right-side elevation view thereof;

FIG. 7 is an exploded top plan view thereof; and,

FIG. 8 is an exploded bottom plan view thereof.

The broken lines in the drawings are for the purpose of illustrating environmental subject matter and portions of the power entry connector that form no part of the claimed design.
